UNITED STATES PATENT OFFICE.

WILLIAM J. SHEAFFER, OF LIVERPOOL, PENNSYLVANIA, ASSIGNOR OF ONE-THIRD TO
EMMETT E. BARNER, OF LIVERPOOL, PENNSYLVANIA.

VALVE FOR GAS-ENGINES.

1,229,336.

Specification of Letters Patent. Patented June 12, 1917.

Application filed March 20, 1916. Serial No. 85,445.

To all whom it may concern:

Be it known that I, WILLIAM J. SHEAFFER, a citizen of the United States, residing at Liverpool, in the county of Perry and State of Pennsylvania, have invented certain new and useful Improvements in Valves for Gas-Engines, of which the following is a specification.

My invention relates to explosive engines and pertains more particularly to valves for controlling the intake of the charge and the exhaust from the engine after the explosion.

The object of my invention is to produce reciprocating sleeve valves having a diaphragm in each and an orifice in the wall of each adapted to register with channels leading into the explosion chamber of a cylinder and having an opening in the end of each sleeve structure. Another object of my invention is to provide a plurality of rings around said valve sleeves to prevent the escape of the products of combustion and thus avoid a reduction in the compression. A further object thereof is to provide means for coupling said valves with the piston of an engine so that the intake and exhaust are timed with the action thereof. A still further object of my invention is to produce an engine of said type in which the spark plug may be located in the head of the cylinder and thus impart initial ignition at a point immediately opposite the head of the piston whereby no loss of energy occurs. Another object thereof is to produce means for silently operating said valves and for freely lubricating same; and still another object of my invention is to produce a more simple, cheap and efficient device of the character described than has heretofore been attained. To these ends my invention includes the combination and arrangement of component parts to be hereinafter described and more particularly pointed out in the claim.

In the accompanying drawings, in which like reference characters indicate similar parts:

Figure 1 is a longitudinal sectional view of my cylinder and valve taken on the line 1—1 of Fig. 2.

Fig. 2 is a transverse sectional view of the same taken on the line 2—2 of Fig. 1.

Fig. 3 is a vertical sectional view of the

valve members taken on the line 3—3 of 55 Fig. 1.

Fig. 4 is an end view with the valve-operating gears removed.

Fig. 5 is a detail perspective view of the block carried in one end of each of the sleeve 60 valves.

Fig. 6 is a side view of one of the sleeve valves; and

Fig. 7 is a side elevation of my engine.

Referring now to the drawings, 1 indicates a metal casting in which the cylinder chamber 2 is provided, adjacent to which and offset therefrom are provided the cylindrical valve chambers 3 and 4 each of which communicate with the cylinder chamber 70 through the channels 5 and 6 adjacent to the head of the cylinder chamber and at right angles to the bore thereof.

Said cylinder chamber is closed at one end by the head 7 in which a threaded orifice 8 75 is provided for the introduction of the spark plug 9.

As shown in the drawings, suitable water chambers are provided in the walls of the cylinder and valve chambers to keep the 80 parts cool. Each of my valve members 3 and 4 comprises a sleeve 11 having a diaphragm or partition 12 intermediate of its ends dividing the sleeve into two chambers 13 and 14. The chamber 13 is entirely open 85 and unobstructed at its outer end and adjacent to said diaphragm 12 an opening 15 is provided in the wall of the sleeve adapted to register with the channel 5 or 6 at predetermined time in the reciprocation of the 90 sleeve, as hereinafter described. Surrounding the portion of said sleeve occupied by the diaphragm 12 and chamber 13 is provided a plurality of annular grooves 23 and 24 in which packing rings 16 may be carried to prevent the escape of gas from the chamber 2. The opposite end of the sleeve is closed with block 17 held in position by the pin 18 and the valve rod 19 is secured in said block by said pin. Said block 17 is 100 provided with a plurality of longitudinal grooves 20 through which lubricating oil is readily passed from the interior of the chamber 14 of the sleeve and said chamber is surrounded by a plurality of annular grooves 105 25 having a plurality of orifices communicating with the interior of the sleeve. Lubricating oil is communicated to the valve.

cylinder and sleeve from the chamber 21 through the openings 22 and thence is distributed longitudinally by the annular grooves 25 and finds its outlet through the 5 chamber 14 and the longitudinal grooves 20 in the head block 17. Suitable connection, not shown in the drawing, may be provided between the oil chamber 21 and the interior 14 of each valve sleeve.

10 A piston rod 25 is attached at one end to the piston 26 and at its opposite end is attached to the crank shaft 27. Said crank shaft may be geared or coupled with the valve-operating shaft 28 in any suitable and 15 sufficient manner. In the embodiment shown a sprocket wheel 29 is carried on the crank shaft and a sprocket wheel 20 is carried on the cam shaft 28 which are connected by the chain 31. The cams 32 and 33 are 20 carried on the shaft 28 in continuous contact with the valve rods 19 and 19' attached to the sleeves, as hereinbefore described. Each of said valve rods is provided with a head 19^a and 19^b, between which and the wall 34 25 are interposed the compression springs 35 and 35' adapted to normally hold the heads 19 and 19' in contact with the faces of said cams. The construction thus described will reciprocate said sleeves in such timed relation to the reciprocation of the piston 26 as to alternately permit the intake of fuel 30 and the exhaust of the products of the explosion through the ends of the sleeves and the communicating openings between the 35 head of the cylinder and the co-operating sleeve valves.

It will be appreciated that one of the cylinder sleeves will communicate with the manifold 38 while the other discharges into 40 the atmosphere and that my sleeve valves thus described will regulate the intake and discharge of fuel and products of combustion in perfect timed relation to the operation of the piston 26; that the spark plug is 45 located in a position wherein no loss of power from the explosion occurs and that no possible loss of compression can be had from the explosion; and it will be further

appreciated that the construction and relation of my valves with the cylinder will be 50 likely to effect an economy in the amount of fuel; that there will be less likelihood of the accumulation of carbon resulting from the products of explosion; that there will be no 55 occasion for the grinding of the valves to preserve compression and that deficiencies in engines of said character resulting from the use of puppet valves in the salient points of their construction may be obviated by the valves of my construction wherein their action is more positive and direct.

Having thus described my invention, what I claim as new and desire to be secured by Letters Patent, is:

In an explosive engine, the combination 65 with a cylinder and a reciprocable piston carried therein; of a plurality of tubular valve chambers adjacent to said cylinder having a channel communicating between the explosion chamber in the cylinder and 70 each of said sleeve chambers at right angles to the pistons, a sleeve reciprocably carried in each of said valve chambers having an opening in its outer end, a block removably carried in its inner end having longitudinal 75 channels through same, a lubricant chamber located between said cylinder and valve chambers having openings into said valve chambers, a plurality of annular grooves surrounding said sleeves having orifices communicating with the interior of the sleeve, whereby lubricant is communicated from the lubricant chamber to the valve chambers; distributed longitudinally by the annular 80 grooves and discharged through the orifices 85 in the walls of the sleeves and the channels in the end blocks, and means for alternately reciprocating said sleeve valves in timed relation to the action of the piston, substantially as described.

In testimony whereof I hereby affix my signature in the presence of two witnesses.

WILLIAM J. SHEAFFER.
